MECHANICAL MOVEMENT

Arthur Robert Clark, Hamilton, Ontario, Canada

Application September 20, 1944, Serial No. 554,983

2-Claims. (Cl. 74—30)

This invention relates to a new mechanical movement.

The mechanical movement of the present invention is primarily intended to produce constant rotary movement from reciprocal rectilinear movement and particularly when the latter motion is produced by leverage, as in a hand-car for instance. The new movement is a substitute for the connecting rod.

The object of the invention is to provide a new mechanical movement whereby dead centres are eliminated in producing rotary motion from reciprocal motion, thereby effecting a constant rotary motion without enlisting the fly-wheel or other momentum producing agents.

Thus it will be evident that a gear, for instance, will revolve evenly and at uniform speed under reciprocal rectilinear urge, the latter motion being effected by any means.

With the above and other objects in view as will be hereinafter apparent, the invention consists in general of certain novel details of construction and combinations of parts hereinafter fully described, illustrated in the accompanying drawing and specifically claimed.

In the accompanying drawing like characters of reference indicate like parts in the several views, and:

Figure 1 is a side elevation of an apparatus constructed in accordance with the present invention and showing a certain rectilinearly reciprocal member at one terminal point of its stroke.

Figure 2 is a similar view showing said member in an intermediate position during its progress to the opposite terminal point of its stroke.

Figure 3 is a similar view showing the member in an intermediate position in its return stroke.

In its present embodiment the invention consists of a rectangular frame 10 constituting a double rack, the two banks of teeth 11 of which are opposed, or face each other.

The frame is interposed between two suitable guides having webs or other planes, and along its range in these guides the frame is adapted to slidably reciprocate. During one complete stroke the frame slides on the web 12 of the lower guide 13, and the upper bank of teeth gears with a pinion 14, as in Figure 2, while during the complete return stroke it becomes elevated and slides along the web 15 of the upper guide 16, and the lower bank of teeth gear with the pinion, as in Figure 3, the pinion and its shaft 17 being on a fixed axis.

Thus it is evident that the differential between

the width of the frame and the interval between the guide webs equals the interval between the pinion 14 and one bank of rack teeth when the opposite bank and the pinion are engaged.

Pivoted to the lower rack bar of the frame 10 are pendent skids 18. These skids are splayed to provide broad lower surfaces, and the corners are preferably rounded. The upper portions of the skids are also rounded, but on arcs described about the axes of the pivot pins 20.

Also on the lower rack bar are stopping blocks 21 disposed to one side of the skids so that one side of each is intimate with the adjacent edge of a skid when the latter are in dependent position, as will be observed in Figures 1 and 3.

In the lower web or plane 12 are recesses 22 which are spaced uniformly to the spacing of the skids 18 and into which the skids fall at the termini or dead centres of the frame strokes.

In Figure 1, which shows the frame at one dead centre of its stroke, the skids are seen thus located, while it will also be observed that the profiles of the recesses substantially conform to the penetrating portions of the skids with the exception, however, that one rim of each recess is rounded to form a mounting ramp 23.

During the stroke of the frame 10 shown in progress in Figure 2, which will be termed the forward stroke, the frame as has been previously

specified slides on the lower web 12, while the skids 18 trail along the same web having been swung to trailing position by their movement out of the recesses 22 enforced by the forward movement of the frame away from back dead centre.

Thus during the forward stroke of the frame the skids are idle, and the upper bank of rack teeth are meshed or geared with the pinion 14, imparting rotation thereto.

At forward dead centre of the frame the trailing skids fall into respective recesses and their forward edges immediately become intimate with the sides of the stops 21.

The reverse or back stroke follows, whereupon the skids 18 being prevented by the blocks or stops 21 from swinging in the opposite direction are caused to mount the ramps 23 and in their dependent but now laden position to slide along the web 12, as in Figure 3.

At the same instant of this action the frame 10 is shifted to an elevated level away from the lower web and in intimacy with the upper web. In this path the frame remains during its back stroke but at the terminus of that stroke the skids fall into respective recesses and the frame again shifts to the lower level by gravity.

At the instant of the shift of the frame to high level the upper bank of rack teeth are demeshed with the pinion and at the same instant the lower teeth become geared. Thus it is evident that the alternate and forward back strokes or reciprocation of the frame or double rack imparts continuous directional movement to the pinion without perceptible pause or speed fluctuation.

Obviously the driven pinion 14 may be utilized for effecting like motion to any part of a machine, apparatus or vehicle, such as an axle, and similarly the pinion driving double rack may receive its driving force from any reciprocal device such as the lever 24, here shown as an example, fulcrumed to a fixed member 25 and connected to the frame 10 by the link 26.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed:

I claim:

1. In an apparatus for producing constant rotary movement from reciprocal rectilinear movement, a double driving rack arranged for reciprocal rectilinear movement in horizontal guide means and consisting substantially of a frame provided with upper and lower internal banks of rack teeth, said guide means including a slide for the frame and having spaced recesses, pendent skids pivoted to the frame and arranged to swing in one direction from dependent position, stop means precluding swing of the skids in the opposite direction from dependency, and a driven pinion on a fixed axis between said banks, said frame being arranged to glide on said slide throughout its strokes in one direction with the skids trailing and the upper bank of rack teeth geared to the pinion and the other free, said frame being arranged to move throughout its strokes in an opposite direction at an elevated level with the skids supporting it and gliding on said slide and the lower bank of rack teeth geared to the pinion and the other free, said skids being received in said recesses at the termination of each stroke of the frame.
2. The device defined in claim 1 wherein the recesses are rounded to form ramps for the skids in mounting to the slide.

ARTHUR ROBERT CLARK.
